CLAIM

The ornamental design for a tableware set, as shown and described.

DESCRIPTION

FIG. 1 is a front perspective view of the first component of a tableware set;

FIG. 2 is a rear perspective view thereof;

FIG. 3 is a front view thereof;

FIG. 4 is a rear view thereof;

FIG. 5 is a left side view thereof;

FIG. 6 is right side view thereof;

FIG. 7 is a top view thereof;

FIG. 8 is a bottom view thereof;

FIG. 9 is an enlarged detail view taken from portion "9" on FIG. 1;

FIG. 10 is a front perspective view of the second component of a tableware set;

FIG. 11 is a rear perspective view thereof;

FIG. 12 is a front view thereof;

FIG. 13 is a rear view thereof;

FIG. 14 is a left side view thereof;

FIG. 15 is right side view thereof;

FIG. 16 is a top view thereof;

FIG. 17 is a bottom view thereof;

FIG. 18 is an enlarged detail view taken from portion "18" on FIG. 10;

FIG. 19 is a front perspective view of the third component of a tableware set;

FIG. 20 is a rear perspective view thereof;

FIG. 21 is a front view thereof;

FIG. 22 is a rear view thereof;

FIG. 23 is a left side view thereof;

FIG. 24 is right side view thereof;

FIG. 25 is a top view thereof;
 FIG. 26 is a bottom view thereof;
 FIG. 27 is an enlarged detail view taken from portion "27" on FIG. 19; and,
 FIG. 28 is a front perspective view showing the tableware set in a combination state.
 The broken lines in the drawings illustrate the portions of the tableware set, which form no part of the claimed design. The dash-dot-dash broken lines encircling the enlarged views are for annotative purposes only and form no part of the claim thereof.

1 Claim, 28 Drawing Sheets
